UNITED STATES PATENT OFFICE.

HARVEY D. GEYER, OF DAYTON, OHIO, ASSIGNOR TO THE INLAND MANUFACTURING COMPANY, OF DAYTON, OHIO, A CORPORATION OF DELAWARE.

HEAT-INSULATING LID.

Application filed February 19, 1927. Serial No. 169,668.

This invention relates to removable lids, and particularly to lids for closing the openings in the top of ice cream cabinets provided to afford access to the ice cream cans 5 therebelow.

In applicant's co-pending application, Serial No. 154,910, filed December 15, 1926, there is disclosed a form of lid having a molded composition cupped bottom plate, a 10 sheet metal top plate, and a separately molded hand-knob with a molded-in metal insert to secure the top and bottom members together. The present invention presents 15 advantages over the former construction in the following: There is only one molded piece instead of two; the sheet metal bottom plate which is ordinarily made of Monel metal, is smaller and hence less expensive in material used; also this bottom plate is 20 of such size that it can be made from the scrap pieces of Monel metal which are cut out to form the holes in cabinets having Monel metal covered tops; the soft rubber 25 gasket may be easily applied or removed simply by stretching it slightly and snapping it into its groove and hence replacement of these gaskets, which is necessary from time to time, is a much more simple matter than in the former construction; 30 the periphery of the sheet metal plate has a pressed fit upon the periphery of the molded flange and a tight joint is thereby made which prevents moisture from entering the heat insulation material in the lid and bad 35 odors escaping therefrom.

Further objects and advantages of the present invention will be apparent from the following description, reference being had to the accompanying drawings wherein a 40 preferred embodiment of one form of the present invention is clearly shown.

In the drawings:

Fig. 1 is in part a side elevation and in 45 part a vertical section through a lid for an ice cream cabinet made according to this invention; and

Fig. 2 is a bottom view of the molded member of the lid with the rubber gasket removed.

Similar reference characters refer to similar parts in the several views.

Referring to the drawings, 10 designates the molded top member or main body of the lid which has a depending annular flange 11 molded integrally therewith. Also molded 55 integrally therewith is the central hand-knob 12 and a central depending projection 13 which preferably extends slightly below the bottom face 14 of flange 11. The interior chamber 15 of member 10 is filled with 60 a suitable insulating material 16, such as loose ground cork or ground cork board.

The bottom plate 20 is made from quite heavy sheet metal, preferably Monel metal. These plates 20 are of such size, as clearly 65 indicated in Fig. 1, that they can be made from the round scrap pieces which are cut out of the metal covering of the cabinet top 21 to form the holes into which the lid fits. The bottom plate 20 is provided with 70 a peripheral upstanding flange 22 which telescopes snugly upon the lower end of the molded flange 11 with a tight fit. Preferably a small shoulder 23 is molded in the tapered exterior surface of flange 11 against 75 which the top edge of the metal flange 22 abuts when the plate 20 is pressed to position on the molded member 10, thus forming a tight and neat joint. A small clearance 24 between the bottom face 14 of flange 80 11 and the metal plate 20 insures the desired tight fit at the shoulder 23, as will be clear from the drawings. The central portion of plate 20 is preferably secured to the bottom face of projection 13. This may 85 be easily done by a counter-sink headed wood screw 25. The metal plate 20 has the Monel metal bent up around the hole for screw 25 so as to form a countersunk recess 90 26 for the screw head. When screw 25 is driven home, the countersink 26 of the metal plate 20 is very firmly wedged within the countersink recess in the projection 13, and thus a very tight joint around the screw 25 is obtained. It is desirable that the 95 interior chamber 15 be quite perfectly sealed in order to prevent moisture entering the heat insulating material 16 and causing de-

terioration thereof and a subsequent escape of bad odors therefrom which would be readily absorbed by the ice cream in the container below.

- 5 A gasket channel 30 is molded in the member 10 in the position clearly shown in Fig. 1. An endless soft rubber gasket 31 is provided of such size that it can be stretched slightly during applying thereof and will 10 then snap into groove 30 and fit snugly therein. The flat rectangular shape of the cooperating gasket and groove causes the gasket to hold its proper position therein and renders it less liable to accidental dis- 15 placement when the lid is handled carelessly. This gasket 30 of course supports the weight of the lid upon the top 21 of the cabinet and gives a good air seal for the cold compartment below. These gaskets 30 20 require replacement after a period of service. This is done simply by removing the gasket with one's fingers and snapping the new gasket in place.

Preferably the radially projecting flange 35 overlying the gasket 31 is strengthened and protected by a molded-in channel metal ring 36, preferably rolled up from Monel sheet metal. This sheet metal ring 36 is first rolled substantially to shape so that it 30 will fit snugly within the mold cavity for the flange 35 when inserted in the mold. No joint is made in the ring where the ends 38 abut in order to permit the ring to expand slightly in diameter to hug the cavity 35 walls when the molded material is forced thereagainst with great pressure in the process of molding the member 10. It is thus seen that the ring 36 is easily and securely molded in place upon the flange 35. If desired, the top portion of ring 36 may have perforated letters 37 or other designs therein. In such case the molded material will flow through the perforations during molding and lie flush with the outer surface of the metal ring 36, thus giving an inlay effect of the letters or other designs, which are ordinarily of black molded material. Such inter-locking of the molded material with the metal ring 36 also more securely anchors 50 the ring to the molded material, as will be obvious.

The molding composition of which member 10 is made is preferably an asphaltic composition consisting approximately of the following materials and proportions by weight: gilsonite (Utah asphalt) 46%; Korite (a bituminous residue of low melting point derived as a by-product of petroleum refining and marketed extensively by the Standard Oil Co. of Indiana) 11½%; disintegrated asbestos fiber 19½%; and an inert filler such as infusorial silica, powdered slate, fine clay, powdered asbestos, or other suitable filler, 23%. These materials

are converted into a substantially homogeneous plastic doughy mass in a suitable heated mixing or kneading machine at a temperature around 385° F. and then the proper amount of this hot compound is put in the unheated lid mold of the closed type 65 and formed under a high pressure in the 70 molded material. This pressure may range from something like 3,500 to 10,000 lbs. per square inch and is so high that the material is substantially immediately hardened there- 75 by. After about three minutes, the molded part can be removed from the mold and permitted to cool down to room temperature. This cold molding material is described and claimed in a separate co-pending applica- 80 tion, Serial No. 169,669, filed February 19, 1927.

While the form of embodiment of the present invention as herein disclosed, constitutes a preferred form, it is to be understood that other forms might be adopted, all 85 coming within the scope of the claims which follow.

What is claimed is as follows:

1. A removable heat insulating lid for a 90 container comprising: a one piece molded composition top member having a hand knob and an annular downwardly extending flange molded integral therewith, and an integral centrally located depending projection, a sheet metal bottom member secured to said flange and projection, and heat insulating material in the chamber formed between said top and bottom members.

2. A removable heat insulating lid for a 100 container comprising: a one piece molded composition top member having a hand knob and an annular downwardly extending flange molded integral therewith, said top member having a peripheral shoulder 105 and an annular groove immediately adjacent thereto on the outer face thereof, an endless soft rubber gasket supported in said groove and against said shoulder for supporting the weight of said lid, a sheet metal bottom 110 plate secured to said flange, and heat insulating material in the chamber formed between said top member and bottom plate.

3. A removable heat insulating lid for a 115 container comprising: a molded composition top member having a projecting peripheral edge adapted to rest upon the opening in the container to support the weight of the lid, said peripheral edge having a sheet metal protective ring molded in place in the 120 molded material.

4. A removable heat insulating lid for a 125 container comprising: a molded composition top member having a projecting peripheral edge adapted to rest upon the opening in the container to support the weight of the lid, said peripheral edge having a channel shaped metal ring enclosing and protecting

the same and anchored in place by being molded in situ in the molded material.

5. A removable heat insulating lid for a container comprising: a molded composition top member having a projecting peripheral edge adapted to rest upon the opening in the container to support the weight of the lid, and a channel shaped metal ring en-

closing said peripheral edge and molded in place in the molded material, said metal ring having perforations therein filled with the molded material, whereby inlay designs are obtained in said metal ring. 10

In testimony whereof I hereto affix my signature.

HARVEY D. GEYER.
